VACUUM DIFFUSION PUMP

Richard B. Nelson, East Orange, N. J., assignor
to Radio Corporation of America, a corporation
of Delaware

Application August 31, 1939, Serial No. 293,911

8 Claims. (Cl. 230—101)

My invention relates to diffusion pumps for producing high vacuum and particularly to diffusion pumps which use organic working fluids, and especially organic working liquids such as oil, which contain relatively volatile substances.

An object of my invention is an improved diffusion pump which separates the various constituents of the oil or other working liquid according to volatility, and delivers the separated constituents to different nozzles, and removes contaminated liquids and high vapor pressure residues from the pump. For example, hydrocarbons that are produced by decomposition during heating and condensing of oil used as a working liquid are trapped and removed from the pump.

A further object of my invention is a pump which has a high pumping speed, will produce high ultimate vacuum, and will work against a comparatively high backing pressure, and also is mechanically rugged and commercially feasible for factory and laboratory applications.

The invention is defined with particularity in the appended claims and preferred embodiments are described in the following specification and shown in the accompanying drawing in which Figure 1 shows a vertical sectional view of one pump embodying my invention and Figure 2 shows a vertical sectional view of another pump embodying my invention.

Chamber 1 of my novel diffusion pump communicates through an inlet port 2 at its upper end with the envelope to be evacuated and communicates through outlet port 3 with a preliminary or so-called "rough pump." The "rough pump" is commonly referred to in the art as the fore pump or the backing pump. Pumping fluid 4, heated in the boiler in the bottom of the pump by an electric heater such as shown at 5, is vaporized and expelled in a downwardly directed jet from the annular nozzle 6. The nozzle 6 is formed by supporting sleeves 7 and 8 with their rims coaxial and flared to leave an annular opening. A downwardly directed jet of pumping fluid vapor is condensed on the cooled walls of the cylindrical condenser 9 centrally depending, according to Figure 1, from a disc 10 sealed gas-tight into the upper end of the chamber. Condenser 9 comprises two concentric tubes with liquid cooling ports to the annular space between the tubes. Sleeve 8 of the outer nozzle is spaced inwardly from the chamber wall to allow it to run hot and thus prevent condensation of vapor on the sleeve. The second nozzle 11 comprises a tube supported at its lower end on tube 7 with its upper end extending into and concentrically spaced from the wall of the lower end of cylinder 12. Cylinder 12 is preferably thin sheet metal and supported by a ring 13 of metal or good heat conducting material joined to the lower end of the condenser 9. Any supports or braces for

tube 12 above ring 13 should be of good heat insulating material so that tube 12 is cooled only at its lower end. The housing 14 comprising the inner wall of the condenser encloses the outlet end of cylinder 12 and communicates through port 3 to the fore pump.

Gas molecules entering the chamber from the inlet port are entrained by the downwardly directed vapor from jet 6 and impelled toward the next jet. The vapors condense upon the cooled condenser wall releasing the gas molecules which are then entrained toward the exhaust port by the next jet.

My novel pumping device is constructed to fractionally distill the fluid in the bottom of the chamber and selectively supply the different fractions to the different nozzles, so that only the most phlegmatic constituents are admitted to the nozzle nearest the vacuum end of the chamber, the more volatile constituents being directed to the nozzle nearest the outlet port. Condensate from both nozzles drains down the inner surface of sleeve 7 to the junction with tube 11, and hence to the center of the boiler through the liquid trap in pipe 15. Pipe 15 may drop the oil to the top of a stack of screens comprising, preferably, cones of wire mesh, piled with alternate cone inverted so that the oil trickles downward and wets all of the screens. Vapor rising from the boiler picks up and carries away the high volatiles on the screen much in the manner of the reflux still. Tubes 7 and 8 within the cylinder are set in liquid-tight contact with the bottom plate of the chamber to divide the lower end of the pump into concentric vapor generating compartments 16 and 17. Small openings 18 of such size are made in the lower end of tube 7 below the liquid level to permit slow flow of liquid from chamber 16 into 17 at the rate at which oil evaporates in chamber 17. The most volatile constituents of the pumping fluid drained into the inner compartment have sufficient time to vaporize in the inner compartment and be conducted away to the nozzle 11 before these constituents may flow into compartment 17. Hence the constituents of lowest volatility are directed to nozzle 6.

To place in operation the desired pumping fluid is poured into the pump, the inlet port is connected to the envelope to be evacuated, the outlet port connected to a fore pump, cooling water is circulated in condenser 9 and the temperature of the bottom plate of the chamber raised to a point slightly above vaporization temperature of the most phlegmatic constituent of the pumping fluid. A jet of vapor of relatively high velocity is directed downwardly by nozzle 6 and upwardly by nozzle 11, each nozzle receiving only the desired constituent of the pumping fluid. The first nozzle discharges the entrained

gas molecule to the space below the end of the condenser and nozzle 11 draws the gas upwardly through cylinder 12 and discharges the gas in the housing 14 where the gas is removed by a fore pump. The vapor from nozzle 11, however, condenses on the wall of cylinder 12 and returns to the boiler, the heat given up by the vapor serving to keep the cylinder at a temperature above the condensing temperature of the contaminating volatiles or "light ends" of the pumping fluid which appear as a result of decomposition of the fluid. The much cooler walls of housing 14, however, condense these volatiles and drain them into the trap between the lower ends of cylinders 12 and 9 where they remain inactive. It has been found that oils used over and over in my improved pump never accumulate deleterious high vapor pressure constituents, such as volatiles and light ends, as the pump in operation continually purifies the oil.

The vacuum pump shown in Figure 2 embodies the characteristic features of my invention with some of the parts rearranged. The pump of Figure 2 shows my improved baffle at the input end of the pump directly above an improved high vacuum nozzle 20. Between nozzle 20 and the outlet nozzle 11 is added an intermediate nozzle 21, each nozzle communicating through its individual conduit with the boiler of the pump. The conduits are concentrically arranged to form three concentric compartments 22, 23 and 24 at the lower end, the latter compartment being inside the other two and communicating with the high vacuum nozzle 20. Fractionation of the oil divides the oil into three groups of components and delivers them to their respective nozzles in the manner described, the condensate from each of the nozzles draining down the wall of chamber 1 and through openings in the lower end of the sleeve 25. Vapors of the lighter fractions mixed with contaminating volatiles and "light ends" pass to nozzle 11 and are discharged in a stream in the lower end of cylinder 12 where the vapor entrains the gas from nozzle 21. Cylinder 12 is cooled at its lower end adjacent nozzle 11, its walls being held free of the walls of housing 14 so that the cylinder may be heated by the vapor from the nozzle. As in the pump of Figure 1 the temperature along cylinder 12 is highest at its outer end and coolest at the nozzle end. The temperature gradient between the ends of the cylinder is automatically adjusted by the vapors so that practically all of the vapors is condensed short of the outer end of the cylinder and returned to the boiler. Baffle 26 may be placed across the outer end of the cylinder to stop any vapor that may reach the end of the cylinder. Gas, light end impurities and volatile contaminations, however, pass on into the housing where they are either pumped away by the fore pump or are condensed by the cooler walls of the housing and drained to the bottom of the housing. My improved pump is so effective in separating undesirable volatiles from the pumping fluid that kerosene or gasoline added to an oil pumping fluid commercially known as Apiezon oil is quickly isolated in housing 14.

The high vacuum nozzle 20 found to be most effective comprises a shallow cup or hood 27 fitted over the rim of a sharp edged ring 28 with a small annular clearance between the ring and the skirt of the hood. The diameter of the conduit 29 supporting the ring should be considerably less than the diameter of the hood so that the center of the stream of vapor from the nozzle

flows inwardly toward the center of the pump. The high pumping speed of this nozzle is apparently due to the low number of ambulant vapor molecules flowing upwardly in the pump.

The baffle that cooperates with nozzle 20 to give best unidirectional flow to the gases comprises a plurality of concentric annuli 30, each annulus comprising a ring, preferably tubular in shape and having an outwardly extending radial fin at the lower end of the ring, the fin of each ring underlying the end of the next larger ring. Each fin slopes outwardly and preferably downwardly to permit condensate to drain down into the pump. That portion of the baffle directly above nozzle 20 is closed with a solid shield 31. Gas flowing downwardly in a vertical direction passes between the vertical telescoped sections of the baffle and with one reflection from the radial fins of the baffle can pass to the cooled walls of chamber 1, from whence it enters the stream of vapor from nozzle 20 and is carried downwardly toward the outlet port. Air or gas molecules are delivered directly by the baffle to the open annular space around the nozzle from which the molecules may pass unimpeded into the vapor stream. Any oil molecules, however, traveling upward from the nozzle 20 must, to reach the upper side of the baffle, be reflected twice from cool surfaces of the condenser and baffle. Baffles heretofore in common use deliver the molecules to the space above the end of the high vacuum nozzle, so that the nozzle blocks off a large portion of the effective path through the baffle. The top of my nozzle 20 may be placed close to the baffle without constricting the effective path. Further, elimination of space between the nozzle and baffle of my pump reduces the number of reflections below the baffle and minimizes the resistance to the gas flow.

A pumping speed of 280 liters of gas per second has been attained with a pump constructed as shown in Figure 2 with the following dimensions: The inside diameter of chamber 1 is $4\frac{1}{8}$ inches; the outside diameter of hood 28 is $2\frac{3}{8}$ inches; the clearance between hood 28 and the rim of ring 28 is $\frac{1}{2}$ inch and the distance between the rim of the ring and the lower edge of the hood is $\frac{1}{8}$ inch; the inside diameter of cylinder 12 is 1 inch and its length is 5 inches; and the annular clearance between nozzle 11 and the cylinder is $\frac{1}{2}$ inch. The clearance between the skirt of nozzle 21 and the wall of chamber 1 is $\frac{1}{8}$ inch.

Commercial pumping oil of the type known as "Octoil" when heated with a 500 watt electric heater pumped gas at the rate of 280 liters per second and obtained ultimate vacuum at 1×10^{-7} mm. of mercury measured with an ionization gauge calibrated with air. The chamber wall 1 of this pump is brass .065 inch in thickness and the nozzle tubes and cylinder 12 are steel .030 inch in thickness. The lower end of the chamber should be insulated to reduce heat loss. The water through the jackets may be tap water at a temperature of about 20° C. At these high pumping speeds the temperature of cylinder 12 was found to vary between 20° C. at the cooled end to about 70-90° C. at the free end. A removable cap should be provided over the outer end of the housing 14 to facilitate removal of residues in the housing.

My improved oil diffusion pump not only separates the various constituents of the oil according to the volatility but removes contaminated oil and high vapor pressure residues from the pump. My pump has high pumping speed, high permis-

sible backing pressure and is capable of high ultimate vacuums. A mechanically rugged pump may be fabricated from commercial metal tubing and may be handled roughly, and is commercially feasible for factory and laboratory uses.

I claim:

1. A vacuum pump comprising a tubular cylinder supported at one end, means to cool only said one end, a tubular nozzle co-axial with said cylinder and extending into said end of the cylinder with an annular space between the rim of the nozzle and the wall of the cylinder, a source of pumping vapor communicating with the nozzle, the inlet port of the pump communicating with said space, a housing enclosing the other end of said cylinder and joined gas tight to the cylinder along a line spaced from said other end, said other end of the cylinder being open and communicating with the interior of said housing, said other end of the cylinder being thermally insulated from surrounding structure of the pump, and being thermally free to be heated by said vapor to a temperature near the condensing temperature of said vapor, and the outlet port of said pump communicating with said housing.

2. A vacuum pump of the diffusion type adapted to employ a mixed organic working fluid comprising a nozzle for projecting a stream of vapor of the working fluid toward the outlet port of the pump, a cylinder open at each end coaxial with said nozzle to receive at one end the vapor stream from the nozzle, means for cooling said cylinder only at said one end, a housing spaced from and enclosing the cylinder, said housing being joined gas tight to the cooled end of the cylinder and communicating with the outlet port of the pump, a boiler for evaporating the fluid, a conduit to conduct the evaporated working fluid to the nozzle, the other end of the cylinder being thermally insulated and free to be heated by said evaporated working fluid, a drain to return condensed fluid in the cylinder to the boiler.

3. A vacuum pump of the diffusion type comprising a tubular pumping chamber, a nozzle for directing an annular stream of the vapor of said fluid along the wall of said chamber toward one end of the chamber, a baffle in close spaced relation with said nozzle and between the nozzle and the other end of the chamber, said baffle comprising a plurality of coaxial annuli, each annulus having a tubular ring concentric with the chamber, the ring being coaxially arranged in spaced telescoped relation, one within the other, and each ring having an outwardly extending radial fin at the nozzle end of the ring, the fin of one annulus spaced from and overlying the end of the next larger ring.

4. A vacuum pump of the diffusion type comprising a tubular pump chamber with an inlet port and an outlet port, a nozzle with an annular opening concentric with the chamber for directing a stream of vapor toward the outlet port, a baffle across the chamber between the inlet port and the nozzle comprising a plurality of annuli concentric with the chamber, each annulus having a tubular ring portion coaxial with the chamber and a radial fin portion extending toward the wall of the chamber, the tubular rings being arranged in spaced telescoped relation and the fin of each annulus overlying the nozzle end of the ring portion of the next larger annulus, the innermost annulus overlying the end of said nozzle and the annular spaces between the fins opening directly to the pump chamber wall opposite said nozzle.

5. A vacuum pump of the diffusion type adapted to employ a mixed organic working fluid comprising a cylinder, a nozzle at one end of the cylinder with an annular space between the rim of the nozzle and the wall of the cylinder, a source of vapor communicating with the nozzle, an inlet port of the pump communicating with the space, the other end of the cylinder communicating with the outlet port of the pump, and means for maintaining a difference in temperature between the ends of said cylinder, means for cooling said cylinder at its nozzle end to a temperature below the condensing temperature of said working fluid, the other end of the cylinder being thermally insulated and free to be heated by said working fluid to a temperature intermediate the condensing temperature of the working fluid and the temperature of volatile constituents in said fluid.
6. A vacuum pump of the diffusion type adapted to employ an organic pumping fluid, said fluid containing gas, light ends and impurities more volatile than said fluid, an elongated cylinder, a nozzle at one end of said cylinder for projecting a stream of vapor of said fluid with its impurities toward the other end, a generator for vaporizing said fluid and means for conducting said vapor to said nozzle, means to maintain said one end of the cylinder at a temperature below the condensing temperature of said vapor and means for maintaining said other end at a temperature between the condensing temperature of said impurities and the condensing temperature of said vapor, means at said other end to remove and condense said gas and impurities, and means to return the condensed vapor to said generator.
7. A vacuum pump comprising a tubular chamber with an inlet port and an outlet port, the ports being at opposite ends of the chamber, means to cool the chamber wall, a baffle across the chamber between the inlet port and outlet port comprising a plurality of coaxial annuli concentric with the chamber, each annulus having a tubular ring coaxial with the chamber, the rings being telescoped and concentric with and radially spaced from each other, and each ring having an annular fin at its end toward the outlet port, the fin of each ring overlying the end of the next larger ring, the fins being truncated cones coaxially arranged in spaced nested arrangement and sloped outwardly and toward said outlet port so that the spaces between the fins open obliquely to the pump chamber wall.
8. A vacuum pump of the diffusion type comprising a tubular pump chamber with an inlet port and an outlet port, means to cool the chamber wall, a nozzle with an annular opening concentric with the chamber for directing a stream of vapor toward the outlet port, means to deflect fluid to be pumped, flowing axially along the chamber from the inlet port, into the annular space between the nozzle and the cooled chamber wall comprising a plurality of truncated cones coaxial with said chamber, said cones being graduated in diameter and being in spaced nested relation with the smallest cone closely adjacent said nozzle and the successively larger cones arranged outwardly toward said cylinder wall, the sides of said cones being sloped outwardly and toward said outlet port, so that the space between the cones opens obliquely to the cooled pump chamber wall opposite said nozzle.
